UNITED STATES PATENT OFFICE.

JOHN WINDLER, JR., OF CANTON, KANSAS.

SEED-PLANTER.

SPECIFICATION forming part of Letters Patent No. 433,382, dated July 29, 1890.

Application filed March 24, 1890. Serial No. 345,140. (No model.)

To all whom it may concern:

Be it known that I, JOHN WINDLER, Jr., of Canton, McPherson county, State of Kansas, have invented certain new and useful Improvements in Corn or Grain Planters, of which the following is a full, clear, and exact description, reference being had to the accompanying drawings, forming a part hereof.

My invention relates to improvements in "corn-planters;" and it may be said to consist in the novel construction and combination of its different parts, hereinafter more fully set forth and described.

Referring to the drawings, Figure 1 is a perspective side view of my invention. Fig. 2 is a vertical longitudinal sectional view of my invention, taken on line $\alpha\alpha$ of Fig. 4. Fig. 3 is a vertical longitudinal sectional view of my invention, showing opposite side of its construction from that shown at Fig. 2. Fig. 4 is a top view of my invention. Fig. 5 is a vertical sectional view of the runner and hopper attached. Fig. 6 is a perspective view of the covering for the delivery-chute. Fig. 7 is a perspective view of the box with a portion of its side broken away, showing the perforation through which the grain is deposited by the delivery-cup. Fig. 8 is a perspective view of the extreme end of the marker-shaft. Fig. 9 is a detail perspective view of a portion of the shaft X. Fig. 10 is a detail view of one end of the rocking shaft r and of the parts contiguous thereto. Fig. 11 is a detail perspective view of the central portion of the rocking shaft.

Referring to the drawings by letters, A is a bed-piece having secured thereto two supports a', securely braced by rods e'. Between these supports is bolted the tongue carrying the ordinary draft attachments c d and bolt e. Upon each end of the bed-piece A are secured two runners or furrow-openers B', carrying hoppers B, within which the grain is deposited, the operation of which will be herein-after more fully described. Within the hopper is placed a partition u, having a hole v and covering w, all of which leads to a passage r', formed in the runner or furrow-openers. Secured to the bed-piece A, by bolts or otherwise, is a support D, braced by a bracket G, carrying upon its upper end a seat E for the driver and a foot-rest F. This support is secured by clip k, firmly holding two support-

ing-beams J by an axle K. Journaled within these beams is a sprocket-wheel P, having sprogs or studs Q attached thereto by means of clips R. Studs or projections T, two in number, are secured to the surface of the sprocket-wheel. To each of the supporting-beams is pivoted a latch U, and connected therewith is a rod V, leading to a crank-shaft X, which is operated by the driver's foot depressing the crank Z thereof. This device operates in conjunction with the projections U secured to the sprocket-wheel for locking it in a stationary position.

To the brace D are secured bearings H, within which is pivoted rod I by means of a pin h, said rod having a tail i', which holds the same in its proper position. This rod I is adapted to engage the shaft X by the hook end i, by means of which the sprocket-wheel is elevated and held from the ground. Upon the shaft K and secured centrally thereto is a cam L, having an enlargement l', which operates a shaft r, as will be hereinafter more fully set forth.

Upon one end of the shaft K is a small sprocket-wheel M, over which a chain N runs to a second sprocket-wheel O, secured to the shaft carrying the sprocket-wheel P.

From the bed-piece A extends a bar p, within which the rocking shaft r is journaled. To this rocking shaft is secured an arm b', hinged to a sliding bar z, carrying upon its upper end a roller a'. This bar is securely held in position and allowed to slide by means of the box or keeper y, secured to the bed-piece. A spring c' is also secured to the bed-piece, the free end of which bears against the under surface of the arm b', and holds the roller against the cam L. The shaft r extends entirely across the machine, the ends of which lead to a journal in the hoppers B. To the shaft r are secured two arms s, at right angle therewith, and upon the ends of the said arms are secured cups t, which when operated deliver the grain through openings v in the plate or partition u to the feed-passage r'. Upon the tongue b is movably secured a clip f, within which is journaled a marker-bar l', by means of a bolt h', said clip being secured in position by means of the bolt g. To the opposite end of the marker-bar is secured a spacing device or hill-indicator m, having sprogs n upon the upper and under

surfaces thereof. From the rear of the spacing device is secured a measuring-reach, upon which is placed a series of figures that correspond with numbers to be placed upon the 5 sprocket-wheel. (Not shown.) These figures are so arranged that the driver can see when the end of the row is approached, the two numbers corresponding, and by this means a regular starting-distance can be obtained.

10 In carrying out my invention, it will be seen that the sprocket-wheel with sprogs or studs attached pass over the ground in a step-like motion, keeping the small sprocket-wheel in motion by means of the chain passing over 15 the large sprocket-wheel.

When the corn-planter is being moved from one place to another, the spong-wheel is raised from the ground and is held in that position by hasp-rod I, the end of which drops 20 under the shaft X, and holds it up, as indicated by dotted lines in Fig. 2. When it is desired to arrest temporarily the motion of the sprocket-wheel P, the driver places his 25 foot on the right-angle lever Z, throwing the latch U in contact with the surface of the sprocket-wheel, causing the projections T secured thereto to come in contact with the said latch holding the sprocket-wheel and preventing it from rotating. In this position, the 30 sprogs opposite the projections drag or scratch the ground, making a mark. This operation is carried out at the end of the row, and is done in order that when the planter is 35 turned around ready for starting a new row, the mark thus made may serve as a starting-point by means of which it may be properly spaced.

When the planter is turned around, the marker-bar l is elevated, and is then dropped. 40 The under prong, during the travel of the planter, makes a mark, by which means the rows are made an equal distance apart.

The cam L, which is secured upon the shaft K, causes two hills of corn to be dropped 45 from the hoppers B B, (shown clearly in Fig. 4,) one of the said hills being dropped from each of the hoppers, as will be now described. It will be observed that as the cam moves round it presses down on the pulley a', which 50 is attached to the rocking shaft r, causing a sufficient quantity of corn to be thrown up through the openings or perforations in the bottom or inclined portion of the catch-box u by the cups F to form a hill. Teeth d' d'

project downward from the bed-piece A and 55 serve to sweep out of the path of the sprocket-wheel P any wire, brush, limbs of trees, &c., which would be entangled therein. When the cam is revolved, the cups are pressed down into the grain contained in the hopper, 60 and thereby filled, and during the farther revolution the grain is elevated and thrown into the catch-box u. From thence it passes through an opening or channel r', formed in the runners or furrow-openers. 65

Having fully described my invention, what I claim, and desire to secure by Letters Patent, is—

1. In a grain-planter, the combination of the shaft K, and cam L, attached thereto, and 70 means whereby the same is revolved, the shaft r, secured in the bearing P, said shaft carrying the cup t for delivering the grain, and the arm b', hinged to an upright arm z, carrying a roller a', which bears against the 75 said cam, as substantially set forth.

2. In a grain-planter, the combination of the shaft K, carrying the sprocket-wheel M and cam L, the shaft r, journaled to the bed-piece A, and having secured thereto the arm 80 b', said arm carrying upon its end the upright bar z, provided with the roller a', which is caused to bear against the surface of the cam by the spring c' for operating the automatic grain-feeding device, as substantially 85 set forth.

3. In a grain-planter, the combination of the runners B, hoppers B', box u, having hole v, the shaft r, the arm b', secured thereto, the upright bar z, carrying rollers a', the spring c', 90 bearing against the said arm, and the cam L, mounted upon the shaft K, to which motion is imparted by the chain N over the sprocket-wheels O and M, as substantially set forth.

4. In a grain-planter, the combination of 95 the bed-piece A, carrying the support D, the rod I, hinged to the same, and provided with the tail i and hook i', the beams J, secured to the shaft K, and having journaled therein the crank-shaft x, by means of which the 100 sprocket-wheel P is held from the ground, as substantially set forth.

In testimony whereof I affix my signature in presence of two witnesses.

JOHN WINDLER, JR.
